DESIGN FOR A HEAT EXCHANGER

Allen P. Livar, Bronxville, N. Y., assignor to Richmond Radiator Company, Incorporated, New York, N. Y., a corporation of New York

Application December 6, 1934, Serial No. 54,509

Term of patent 14 years

To all whom it may concern:

Be it known that I, Allen P. Livar, a citizen of the United States, residing at Bronxville, in the county of Westchester and State of New York, have invented a new, original, and ornamental Design for a Heat Exchanger, of which the following is a specification, reference being had to the accompanying drawing, forming a part thereof.

The essential feature of the design is the multiplicity of separated series of vertically arranged spaced openings between the radiator sections adjacent the top of the assembly as illustrated in Figure 1.

I claim:

The ornamental design for a heat exchanger, substantially as shown and described.

ALLEN P. LIVAR.
